UNITED STATES PATENT OFFICE

LEO P. BOUCHER, OF BRISTOL, CONNECTICUT

POCKETBOOK HOLDER

Application filed May 14, 1929. Serial No. 362,981.

This invention relates to new and useful improvements in pocketbook holders, and has for its object to provide a simple and inexpensive article adapted for securely retaining a pocketbook within the rear pocket of a pair of trousers.

Generally, the invention consists of a somewhat elongated inverted U-shaped spring metal clasp adapted for tight engagement with the upper end of the pocketbook as arranged within the pocket of the trousers, the outer leg of the clasp at the upper end thereof, being equipped with a button for engagement through the button-hole of the pocket, so as to obviously prevent the upward movement of the pocketbook within the pocket.

An important object of the invention is to provide a simple and inexpensive article of this nature that when in use will positively prevent the pocketbook from becoming accidentally displaced with respect to the pocket.

In the drawing wherein like reference characters indicate corresponding parts throughout the several views:

Figure 1 is a fragmentary perspective of a pair of trousers illustrating a pocketbook arranged within the rear pocket thereof, and secured therein through the medium of my improved holder.

Figure 2 is an edge elevation of the holder.

Figure 3 is an elevational view of the side of the holder equipped with the button.

Figure 4 is an enlarged horizontal section taken substantially upon the line 4-4 of Figure 2, and

Figure 5 is a plan view of the metal blank from which the said elongated and U-shaped clasp is formed.

Now having particular reference to the drawing, my novel holder consists of as previously stated, a somewhat elongated and inverted U-shaped clasp 5 of spring metal, the lower ends of the legs of the clasp being slightly out turned, so as to enable the clasp to be easily engaged over the upper edge of the pocketbook A, as disclosed in Figure 1. This clasp is preferably constructed from a strip of sheet spring metal, as illustrated in Figure 5, the opposite ends thereof being

provided with longitudinal slots 6-6, for the purpose of lightness.

The upper end of the clasp is of somewhat widened formation in order to provide a hand hold to permit the clasp to be easily associated with and removed from the pocketbook. Furthermore, securely attached to one leg of the clasp 5, adjacent the upper end thereof is a button 6 provided for the purpose of securing the clasp to the trousers 55 pocket, as illustrated in Figure 1. Practically all back pockets of trousers are provided with a button-hole, and obviously, after the clasp has been associated with the pocketbook, and the book arranged within the pocket, the button 6 is passed through the button-hole to securely retain the clasp, as well as the pocketbook within the pocket. 60 65

In view of the foregoing description when considered in conjunction with the accompanying drawing, it will be apparent that I have provided a novel, simple and inexpensive pocketbook holder that is well adapted for all of the purposes heretofore designated, and even though I have herein shown and described the invention as consisting of certain detailed structural elements, it is nevertheless to be understood that some changes may be made therein, without affecting the spirit and scope of the appended claim. 70 75 80

Having thus described my invention, what I claim as new, and desire to secure by Letters-Patent, is:

A pocketbook holder of the character described comprising a substantially inverted U-shaped metallic clasp having an enlarged upper connecting portion, a button having a conical base and a centrally disposed extension for engagement with the enlarged end of the clasp and on one side thereof, and a securing element connecting the button and the clasp together. 85 90 95

In testimony whereof I affix my signature.
LEO P. BOUCHER.
